UNITED STATES PATENT OFFICE.

NATHAN KAPLAN, OF COVINGTON, GEORGIA.

BIFURCATED UNION GARMENT.

Application filed August 11, 1920. Serial No. 402,791.

To all whom it may concern:

Be it known that I, NATHAN KAPLAN, a citizen of the United States, residing at Covington, in the county of Newton and 5 State of Georgia, have invented a new and useful Bifurcated Union Garment, of which the following is a specification.

The device forming the subject matter of this application is a bifurcated union garment, and the invention aims to provide a garment which will confine, in a unitary structure, an outer or dress shirt, as distinguished from an undershirt, and a pair of drawers.

15 The invention aims to provide a garment of the kind above mentioned, so constructed that it will be strong and well adapted to withstand wear.

It is within the province of the disclosure 20 to improve generally and to enhance the utility of garments of the kind hereinafter described.

With the above and other objects in view, which will appear as the description proceeds, the invention resides in the combination and arrangement of parts and in the details of construction hereinafter described and claimed, it being understood that, within the scope of what is claimed, changes in the 25 precise embodiment of the invention shown can be made without departing from the spirit of the invention.

In the accompanying drawings:—

Figure 1 shows in front elevation, a device 35 constructed in accordance with the invention; Figure 2 is a vertical section, taken at the crotch, and in the median line of the garment; and Figure 3 is a view similar to Figure 2, but showing a slight modification 40 in the invention.

The numeral 1 denotes a shirt, the term "shirt" being used to designate an outside or dress shirt, as distinguished from an undershirt. The shirt 1 embodies a back 2 and a front 3, connected by side seams 4, the front 3 being divided, if desired, to form flaps 5, connected by buttons and button holes 6, or in any other desired way. A strip 7 of flexible and resilient material, such as 45 open mesh undergarment material, or anything of the like, is let into the back 2 and extends from one side seam 4 to the other, the function of the strip 7 being to render 50 the garment slightly yieldable in the back, so that the garment will not be likely to

be torn when the wearer sits down or assumes an extreme stooping posture.

Front pieces 8 are provided, the same being made out of open meshwork material, or some other material commonly employed in the making of drawers, as distinguished from the material used in the making of an outside shirt. The front pieces 8 are connected at their upper edges as indicated at 60 9, to the lower edges of the front flaps 5 of the front 3. Rear pieces 10 are supplied, these parts preferably being made of the same material as the front pieces 8. The upper edges of the rear pieces 10 are connected at 11 to the lower edge of the back 2, it being observed at this point, that the back 2 extends downwardly, a considerable amount, below the lower edge of the front 3. The construction above alluded to strengthens 65 the shirt at the back and affords, in particular, strength to resist tear across the buttocks. The outer edges of the front pieces 8 and the outer edges of the rear pieces 10 are connected to form side seams 12, the outer edges of the front pieces 8 being connected, in their upper portions, as indicated at 14, to the forward edges of the back 2, since the back 2 extends downwardly 70 below the front 3.

A notch 15 is formed in the lower edge of 85 the back 2. The front pieces 8 and the rear pieces 10 are cut away, as indicated at 16, along lines merging into the edges of the notch 15 and into the longitudinal edges of the front flaps 5, to open the garment at 90 the crotch. The inner edges of the front pieces 8 are connected to the inner edges of the rear pieces 10, as shown at 17, to form tubular legs. The connection indicated at 17 may be in the form of a permanent seam. Referring, however, to Figure 3, the pieces 8^a and 10^a are shown as being connected at 95 17^a by means of buttons, and it will be understood that buttons, snap fasteners or anything else, may be used at the point indicated.

The device hereinbefore described combines, in a unitary bifurcated article, an outer or dress shirt and a pair of drawers. The structure will withstand wear and will not interfere with the ordinary movements 105 of the body of the wearer.

Having thus described the invention, what is claimed is:—

A bifurcated union garment comprising a 110

back and a front made of dress shirt stock and connected by side seams, the front being divided to form flaps; a strip of resilient material interposed in the back and extended between the side seams; front pieces connected at their upper edges to the lower edges of the flaps, and rear pieces connected at their upper edges to the lower edges of the back, the front and rear pieces being 10 made of underwear stock, means for connecting the outer edges of the front and rear pieces, and means for connecting the inner edges of the front and rear pieces, to form tubular legs, the connections between 15 the inner edges of the front and rear pieces terminating below the upper edges of the rear pieces, the back having a notch extended upwardly into close relation to the strip of resilient material to enhance the resiliency of the garment in the back, the lateral 20 edges of the notch merging into those por-

tions of the inner edges of the rear pieces which are disposed above the means for connecting the inner edges of the front and rear pieces, the lower portions of the inner edges 25 of the flaps of the front having downwardly diverging edges, and the front pieces being cut away along downwardly diverging lines extending from the downwardly diverging edges of the flaps to the upper ends of the 30 means for connecting the inner edges of the front and rear pieces, thereby to enhance the resiliency of the garment, circumferentially thereof.

In testimony that I claim the foregoing 35 as my own, I have hereto affixed my signature in the presence of two witnesses.

NATHAN KAPLAN.
